(57) **CLAIM**

The ornamental design for a lamp dimmer, as shown and described.

DESCRIPTION

FIG. 1 is a front elevational view of the first embodiment of a lamp dimmer of the design according to the invention; FIG. 2 is a top plan view of the lamp dimmer of FIG. 1; FIG. 3 is a bottom plan view of the lamp dimmer of FIG. 1; FIG. 4 is a left side elevational view of the lamp dimmer of FIG. 1;

FIG. 5 is a right side elevational view of the lamp dimmer of FIG. 1;

FIG. 6 is a rear view of the lamp dimmer of FIG. 1; FIG. 7 is an isometric projection of the lamp dimmer of FIG. 1;

FIG. 8 is a front elevational view of the second embodiment of a lamp dimmer of the design according to the invention; FIG. 9 is a top plan view of the lamp dimmer of FIG. 7; FIG. 10 is a bottom plan view of the lamp dimmer of FIG. 7;

FIG. 11 is a left side elevational view of the lamp dimmer of FIG. 7;

FIG. 12 is a right side elevational view of the lamp dimmer of FIG. 7;

FIG. 13 is a rear view of the lamp dimmer of FIG. 7; and, FIG. 14 is an isometric projection of the lamp dimmer of FIG. 7.

The broken lines shown on the rear surface of each embodiment are included for the purpose of illustrating environmental structure only and form no part of the claimed design.

An electrical cord which does not form part of the invention is shown in phantom in FIGS. 1, 4, 5, 6, 8, 11, 12, and 13.
